Primary Examiner — Robert M Spear*Assistant Examiner* — Ryan Harvey(74) *Attorney, Agent, or Firm* — Westerman, Hattori, Daniels & Adrian, LLP(57) **CLAIM**

The ornamental design for a bicycle rack, as shown and described.

DESCRIPTION

FIG. 1 is an isometric view of a bicycle rack showing our new design.

FIG. 2 is a front elevational view of the bicycle rack of FIG. 1, the rear elevational view being a mirror image thereof.

FIG. 3 is a right side elevational view of the bicycle rack of FIG. 1, the left side elevational view being a mirror image thereof.

FIG. 4 is a top plan view of the bicycle rack of FIG. 1; and, FIG. 5 is a bottom plan view of the bicycle rack of FIG. 1.

1 Claim, 1 Drawing Sheet
